UNITED STATES PATENT OFFICE.

HENRY F. GEHANT, OF CHICAGO, ILLINOIS.

FENCE-POST.

No. 906,522.

Specification of Letters Patent.

Patented Dec. 15, 1908.

Application filed October 14, 1907, Serial No. 397,361. Renewed July 25, 1908. Serial No. 445,341.

To all whom it may concern:

Be it known that I, HENRY F. GEHANT, citizen of the United States, residing at Chicago, in the county of Cook and State of Illinois, have invented certain new and useful 5 improvements in Fence-Posts, of which the following is a specification.

This invention relates to fence posts, and particularly to improvements in posts made 10 of iron or steel.

The object of the invention is to provide improved means for anchoring the post in the ground, said means admitting of withdrawal should it be desired at any time to re- 15 move the posts.

The invention is illustrated in the accompanying drawings, in which

Figure 1 is a side elevation of the post, Fig. 2 is an elevation of the opposite side.

The body of the post consists of an angle 20 bar or shape indicated at 6, which may be made of pressed steel, cast metal or otherwise, and sharpened at the lower end as indicated at 7 so that it may be readily driven 25 into the ground. This post is anchored by means of two curved flukes 8 which may be advanced or retracted through holes 9 in the flanges of the post, near the lower end thereof. The flukes are made of metal suffi- 30 ciently flexible or springy to allow them to be forced or drawn through the holes, and when projected they extend at a right angle to each other and reach a position almost per- 35 pendicular to the post so that they firmly anchor the same in the ground and prevent 40 it from being withdrawn or loosened except by retracting the flukes. The flukes are connected at their upper ends to a band 10 which extends around the post and is shaped 45 to fit the flanges thereof, the connection being made on the inside of the angle.

One flange of the post is slotted lengthwise 45 as indicated at 11, and this slit receives the fence wires or fabric, which is then held in place by bands 12 which are clamped tightly around the post, as well as by an angular cap 13 which has a socket of proper shape to receive the top of the post and which may be driven on the post after the fence wires or 50 fabric is in place.

To advance the flukes into the ground the band 10 is driven down by any suitable means, such as a hammer and block, which advances the flukes through the holes and into the adjacent ground. To retract the 55 flukes, a hook or similar implement is inserted down opposite the post and engaged under the band and pulled up. A shoulder 14 limits the upward movement of the band and prevents the flukes being drawn entirely out 60 of the holes 9.

Posts so constructed can be set even when the ground is frozen, as the sharp point and narrow cross section cuts the ground readily, and the flukes can then be projected, in most 65 cases, below the frost line. The ends of the flukes are rounded and pointed so that they may be more easily driven into the ground.

The slits in the form shown in Figs. 1 and 2 can be made alternately on the right and left 70 flanges, and the posts set alternately right and left, thus anchoring the fence in different directions.

Various modifications of the particular 75 form of anchoring device may be made within the scope of the invention.

I claim--

1. A fence post comprising an angle bar having holes in the sides near the lower end, a band extending around the bar, and mov- 80 able up and down thereon, and anchor flukes connected to the band, and adapted to be advanced or retracted through the holes when the band is moved down or up.

2. A fence post comprising an angle bar 85 having holes in the flanges thereof near the lower end, a band shaped to fit closely around the bar and slide up and down thereon, and flexible flukes connected to the band and extensible through the holes when the band 90 is moved down.

In testimony whereof I affix my signature, in presence of two witnesses.

HENRY F. GEHANT.
